[57] CLAIM

The ornamental design for a playground slide, as shown and described.

DESCRIPTION

FIG. 1 is a perspective view of a playground slide showing my new design;

FIG. 2 is a front elevational view thereof;

FIG. 3 is a rear elevational view thereof;

FIG. 4 is a top plan thereof;

FIG. 5 is a bottom plan view thereof;

FIG. 6 is a right side elevational view thereof, the left side elevational view being a mirror image thereof; and, FIG. 7 is a sectional view thereof; taken along line 7—7 of FIG. 6.

The broken line showing of a support in FIG. 1 is for illustrative purposes only and forms no part of the claim.
